UNITED STATES PATENT OFFICE.

LUTHER D. LOVEKIN, OF PHILADELPHIA, PENNSYLVANIA, ASSIGNOR TO SCHUTTE & KOERTING COMPANY, OF PHILADELPHIA, PENNSYLVANIA, A CORPORATION OF PENNSYLVANIA.

AIR-REGISTER FOR OIL-BURNERS.

1,290,607.

Specification of Letters Patent.

Patented Jan. 7, 1919.

Application filed May 10, 1917. Serial No. 167,848.

To all whom it may concern:

Be it known that I, LUTHER D. LOVEKIN, a citizen of the United States of America, and resident of Philadelphia, in the county of Philadelphia and State of Pennsylvania, have invented certain new and useful Improvements in Air-Registers for Oil-Burners, of which the following is a true and exact description, reference being had to the accompanying drawings, which form a part thereof.

My present invention relates to fluid fuel burners and particularly to the oil burners for large steam generating furnaces of the type employed for marine service, and the object of my invention is to provide simple and effective means for introducing air into the combustion chamber of the furnace about the fuel jet which will permit the amount of air admitted to be regulated as required by the conditions of use, and at the same time will insure a desirable uniformity in distribution and direction of flow of the air introduced with the varying rates of air admission.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of my invention.

Of the drawings:

Figure 1 is a sectional elevation of a portion of a furnace equipped with my invention;

Fig. 2 is a front elevation of the air register proper;

Fig. 3 is a partial section taken on the line 3—3 of Fig. 1; and

Fig. 4 is a partial section taken on the line 4—4 of Fig. 1.

In the drawings: A represents the front wall of the combustion chamber of a steam generating boiler furnace, and A' the aperture therein through which the fluid fuel and air are admitted. Secured to the wall A at the margin of the aperture A' is a casting or housing member B shown as annular in form and provided with a conical air and fuel mixing chamber B', which is directly open at its larger end to the furnace com-

bustion chamber proper and may be regarded as an extension thereof. At its small end the housing member B is formed with an inlet opening B² through which extends the fuel supply nozzle C which may be of the usual form and which is adapted to discharge fluid fuel in a conical jet, the apex of which is closer to the combustion chamber proper than is the apex of the conical chamber B'. Surrounding the chamber B' is an annular equalizing chamber B³ into which air passes from the furnace room through ports B⁴, and out of which the air is discharged into the chamber B' through elongated ports B⁵.

In the preferred construction illustrated the chambers B' and B³ are separated from one another by a conical wall formed of a series of blades or vanes b, which are connected with the housing member B proper by means of an annular member b' to which the outer ends of the blades are secured by bolts or screws b², and which is connected in turn to the housing member B by bolts or screws b³. At their opposite ends the blades b are thickened at b⁴ to abut against one another and are secured to an annular member b⁵ by bolts or screws b⁶. The side walls of the elongated ports B⁵ are formed by the adjacent sides of adjacent blades b, which are spaced apart for this purpose between the thickened end portions b⁴ and the annular member b'. The air register element composed in the particular construction illustrated on the annular members b' and b⁵ and blades b is bodily attached to the housing B by the screws b² and may be bodily removed from the housing B when the screws b² are taken out.

The side walls of each port B⁵ are shaped to deliver sheet like jets of air tangential to a cone substantially coaxial with, and of substantially the same taper as the conical fluid fuel jet, but having its apex somewhat farther in the chamber B' than the apex of the conical fuel jet. With the described arrangement the jets of air intersect the fuel jet adjacent the periphery of the latter. This I have found advantageous in securing the desired combustion. The inner edges of the walls of the ports B⁵ are preferably substantially parallel to the surface elements of the conical fuel jet, as this contributes to uniform combustion conditions. Advantageously the outer edges of the blade b are

rounded off as indicated at b^7 to facilitate the desired regularity of air admission from the chamber B^3 to the various ports B^5 and an avoidance of eddy currents.

- 5 A conical damper D is rotatively mounted on the outer surface of the member B being held against axial displacement by retaining clips E secured to the member B . The member D is formed with a series of ports 10 D' which correspond to the ports B^4 and may be moved into and out of register with the latter by rotating the damper D . By this angular adjustment of the damper D it is possible to throttle the ports B^4 more 15 or less as conditions may require.

In operation air passes into the equalizing chamber B^3 through the ports B^4 from the furnace room which may be under atmospheric pressure, or may be under pressure 20 above that of the atmosphere when the plant is being operated under forced draft. The amount of air entering the chamber B^3 is regulated by the adjustment of the damper D to insure the proper supply of air to the 25 combustion chamber of the furnace. The draft and air supply provisions are advantageously so regulated as to deliver the air against the fluid fuel jet with a velocity greater than the velocity of the fuel, as this 30 tends to minimize the possibility of back firing.

The described arrangement for supplying air to the chamber B' through the ports B^5 insures a highly desirable uniformity in distribution about the axis of the chamber B' of the air thus supplied to this chamber, and a desirable uniformity in the direction of flow of the jets of air discharged through the ports B^5 notwithstanding variations in 35 the amount of air passing through the ports B^5 . The amount of air passed into the chamber B' through the ports B^5 may be varied at will by varying the admission through the ports B^4 to the equalizing chamber B^3 without obstructing or altering the shape of the ports B^5 . The shape and direction of the air jets discharged through the ports B^5 is thus unaffected by the volume of air discharged and the apparatus operates 45 with different volumes of air supplied without any such wire drawing or eddy effects as would result from a regulation of the amount of air supplied by the ports B^5 by throttling or changing the shape of these 50 ports.

The described formation of the cage or ported partition separating the chambers B' and B^3 by the bars b makes possible an accurate and uniform shaping of the ports B^5 at a relatively low cost of manufacture. The bars b may readily be cast with sufficient uniformity in shape and smoothness to make unnecessary all, or at least any material machining or grinding, other than the 60 tapping of the bolt holes in their ends.

While the proportions may be varied to meet different conditions I may state that I have obtained excellent results in practice with apparatus proportioned as shown in the drawings in which the width of the inner edges of the ports B^5 is uniformly one fourth inch from one end to the other of each port. The side walls of the ports B^5 are oblique to the axis of the conical interior of the cage element in which the ports are 75 formed and are preferably of a depth transverse to the length of the ports which is appreciably greater (see Fig. 3) than the width of the inner edges of the ports.

Advantageously a relatively small amount 80 of air is supplied to the chamber B' in the form of jets directed toward the axis of the fuel jet cone near the apex of the latter through the small cylindrical ports B^8 . The air thus provided tends to prevent carbon deposits about the fuel supply nozzle. These ports may advantageously lead from an auxiliary equalizing chamber B^6 receiving air from the furnace room through ports 85 B^7 controlled by an angularly adjustable conical damper F secured in place by retaining clips G . The use of the pressure equalizing chamber B^6 makes the distribution and direction of admission of air passing into the chamber B' through the ports B^8 independent of the extent to which the ports 90 B^7 are throttled.

In accordance with the provisions of the statutes I have illustrated and described above the best form of my invention now 100 known to me.

Having now described my invention what I claim as new and desire to secure by Letters Patent, is:

1. In fluid fuel combustion apparatus, the 105 combination of a casing provided with a conical chamber, elongated unobstructed ports in the wall of said chamber extending parallel to the length of the surface elements thereof, and an equalizing chamber surrounding said conical chamber and connected therewith through said ports, regulable means for supplying air to said equalizing chamber and means for discharging into the first mentioned chamber a fluid fuel 110 jet in the form of a cone substantially coaxial with the wall of the first mentioned chamber and having substantially the same taper as said chamber.

2. In fluid fuel combustion apparatus, the 115 combination of a casing provided with a conical chamber, elongated unobstructed ports in the wall of said chamber extending parallel to the length of the surface elements thereof and having their side walls oblique to 120 the axis of said chamber, and an equalizing chamber surrounding said conical chamber and connected therewith through said ports, regulable means for supplying air to said 125 equalizing chamber and means for discharging 130

- ing into the first mentioned chamber a fluid fuel in the form of a cone substantially coaxial with the wall of the first mentioned chamber and having substantially the same 45
 5 taper as said chamber, all so relatively ar-
 ranged that the air jets discharged by said
 ports intersect said fuel jet and are tangen-
 tial to a cone substantially coaxial with the
 10 wall of the first mentioned chamber, and
 having substantially the same taper as said
 chamber.
3. In fluid fuel apparatus, a casing pro-
 vided with a conical chamber, elongated
 15 ports in the wall of said chamber extend-
 ing parallel in length to the surface ele-
 ments thereof, an equalizing chamber sur-
 rounding said conical chamber and con-
 nected thereto by said ports, distributed air
 20 admission ports in the outer wall of said
 casing opening to said equalizing chamber,
 a conical damper mounted on said casing
 and controlling the last mentioned ports,
 and means for discharging a fluid fuel jet
 25 into said chamber.
4. In fluid fuel combustion apparatus, a
 casing provided with a conical chamber, an
 annular equalizing chamber surrounding
 30 said conical chamber adjacent its apex, a
 main air equalizing chamber surrounding
 said conical chamber at a greater distance
 from said apex, distributed ports connecting
 the first mentioned equalizing chamber and
 35 said conical chamber and directed toward
 the axis of the conical chamber, elongated
 ports connecting the main equalizing cham-
 ber and conical chamber and extending
 parallel to the surface elements of said coni-
 40 cal chamber tangential to a cone substan-
 tially coaxial therewith, means for deliver-
 ing a conical fluid jet into said conical cham-
 ber with its axis substantially coincident
 with the axis of said chamber and its apex
 adjacent the apex of the chamber, and regu-
 45 lable means controlling the supply of air
 to said main equalizing chamber.
5. In fluid fuel combustion apparatus the
 combination of a casing provided with a
 conical chamber and an equalizing chamber 50
 surrounding said conical chamber, and com-
 prising a conical cage separating the two
 chambers and formed of bars secured to-
 gether at their ends and spaced apart be-
 55 tween their ends to form elongated ports
 connecting the two chambers and extending
 parallel to the surface elements of the in-
 inner wall of said cage and regulable means
 for supplying air to said equalizing cham-
 ber.
6. In fluid fuel combustion apparatus the
 combination of a casing provided with a
 conical chamber, elongated unobstructed
 60 ports in the wall of said chamber extending
 parallel to the length of the surface elements
 thereof and each of substantially uniform
 breadth at its inner edge from one end to
 the other, said ports having side walls of a
 65 depth substantially greater than the breadth
 of the port.
7. In fluid fuel combustion apparatus a
 chambered housing formed with an opening
 70 in one side and in combination therewith a
 hollow conical element inserted in said hous-
 ing and formed with peripheral ports and
 having its larger end secured to said hous-
 ing at the margin of said opening, said hous-
 75 ing and conical element being shaped and
 proportioned to provide a pressure equaliz-
 ing chamber in the housing surrounding
 80 said conical element, and said housing be-
 ing formed with air inlet openings in its
 sides and with an opening through which
 fuel may be discharged into said conical
 element through the smaller end of its cone.

LUTHER D. LOVEKIN.
